SUSPENSION CLAMP

Robert L. McCoy, Baltimore, Md., assignor to
Locke Insulator Corporation, Baltimore, Md., a
corporation of Maryland

Application December 1, 1930, Serial No. 499,342

15 Claims. (Cl. 248—31)

The invention relates to supporting devices for transmission lines and has special reference to conductor clamps. It is well known that various types of clamps have been used for the purpose of supporting the conductors of transmission lines, most types being of the rigid variety while others are designed to release their grip and open up in the event of unbalanced longitudinal strain upon the conductor. Ordinarily clamps of either variety are hung at the lower ends of strings of insulators which are capable of limited swinging movement. It is a fact that a suspended cable is never still and that it sways with a combination of movements which bring about bending strains at the ends of the clamp, the result being that, unless the conductor be armored by some suitable special equipment, the outer strands of the cable break, bringing about a condition which is highly objectionable for obvious reasons. In some types of installations it is highly desirable that the holding power of the clamp be controlled within close limits. Clearly this entails an accurate construction which is not only difficult to attain but also expensive on account of the care and time required to shape and fit the clamp parts with precision. In some instances it is desirable that the degree of holding action be capable of variation for some reason or other. Another point which is well recognized is that for supporting conductors of different diameters clamps of different sizes are necessary, thereby necessitating that the manufacturer keep on hand a line of clamps of different sizes at least in so far as regards the conductor receiving channels or grooves. It is with all of the above facts in view that I have devised the present invention which has for its general object the provision of a novel clamp in which the cable, while being restrained from longitudinal movement, is capable of other movements with respect to the clamp so as to avoid the bringing about of the highly objectionable bending strains upon the cable resulting from movements thereof. An important object of the invention is to provide a clamp embodying what may be called a stirrup or cradle-like supporting member within which is loosely confined a stop member in the form of a separable block which is clamped directly upon the conductor with any desired degree of pressure, of course within certain limits, depending upon what is most advantageous under the particular circumstances, the arrangement being such that the clamping block may be said to float with the conductor, the weight of the latter being sustained by only the end portions of the main clamp body or stirrup-like member, these supporting portions being specially designed for the purpose and in such manner as to avoid any mutilation of or other damage to the conductor. Another object of the invention is to provide a clamping block construction in which the effective clamping length may be varied while not altering the actual length. A further object of the invention is to provide a clamp structure of this character in which adaptation for use with conductors of widely differing diameters is effected by the simple expedient of employing clamping blocks having bores of different corresponding diameters, it being unnecessary to make any changes in the size or weight of the main body or support. An additional object is to provide a clamp of this character and having the above pointed out advantages and which will yet be extremely simple and inexpensive to make, easy to apply, positive in action, efficient and durable in service, and a general improvement in the art. To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of my clamp showing it applied to a conductor. 90

Figure 2 is a top plan view, and 90

Figure 3 is a cross section taken on the line 3—3 of Figure 2. 90

Referring more particularly to the drawing I have shown my device as comprising a main clamp body or support indicated as a whole by the numeral 10. This body is of general channel shape in cross section with its end portions 11 grooved to form curved seats 12 for the conductor 13, and with its central portion depressed or downwardly offset as at 14 so as to be out of contact with the conductor which is consequently supported only at the two points 12. From these bearing seats the end portions are flared downwardly as at 15, or bell-mouthed, so as to avoid contact with and the bringing of bending strains upon the cable. The central portion 14 is of greater width than the end portions 11 and constitutes a socket for the reception of the clamping block device indicated as a whole by the numeral 16 which simply fits loosely. The 110

sides of the central portion 14 are extended outwardly at opposite sides of the center to define recesses 17 for a purpose to be described.

A clamp of this general type is primarily intended to be suspended and simply for purposes of illustration I have disclosed the central portion 14 as formed at opposite sides and at its transverse axis with laterally extending trunnions 18 here shown as pivotally engaged within suspension links 19 which are preferably of curved shape with their upper end portions directed toward each other as at 20 and terminating in apertured ears 21 by means of which connection may be made at the lower end of a string of insulators, not shown, by the employment of a bolt for the purpose. The ends of the trunnions are preferably formed with downwardly extending heads 22 which overhang the lower ends of the openings in the links and which operate to prevent separation of the parts. As an additional precaution in this respect, cotter pins 23 may be passed through the trunnions outwardly of the links. While this particular mounting is shown and described it should be understood that the invention is not limited thereto as some other supporting means might be provided if found preferable for any reason.

The clamping block member 16 is formed of separable sections 24 and 25, the former being the lower and the latter the upper, which are grooved, channelled, recessed or otherwise shaped to conform to the cross sectional curvature of the conductor. These members are held in clamping relation to the cable by means of bolts 26 which pass through enlargements 27 and 28 at the corner portions of the separable members, these bolts being represented as each carrying a washer 29 and having screwed thereon a pair of nuts 30 and 30^a between which is an additional washer 31. The bottom of the central portion 14 is formed with openings 32 for the passage of the washers 29 and nuts 30 but it will be noted that the washers 31 are of greater diameter than the openings 32 so as to prevent the block device 16 from rising out of the socketed central portion 14 of the main body. The underside of the member 24 is shown as having a slight boss or projection 33 at each opening 32, and the upper member 25 has its top surface formed with shoulders 34 against which the heads of the bolts 26 engage and which therefore operate to prevent the bolts from rotating while the nuts are applied or removed as the case may be. The lateral enlargements 27 and 28 on the members 24 and 25 respectively are received within the above described recesses 17 defined by outwardly offsetting the sides of the central portion 14 at intervals. The engagement of the projections within these recesses will operate positively to prevent any longitudinal displacement of the block device 16 with respect to the main body of the clamp.

To apply the device, the members 24 and 25 are engaged upon the conductor at the desired point, the bolts 26 are passed through the members 24 and 25, with the heads of the bolts engaging at one edge against the respective shoulders 34, subsequently to which the washers 29 and nuts 30 are applied, the latter being screwed down as tightly as may be necessary to bring about the desired degree of clamping action. The main body or stirrup member is then placed in position beneath the block device 16 and moved upwardly with respect thereto so that the lower ends of the bolts 26 and the nuts 30 will pass

through the openings 32, the block device 16 then fitting loosely within the central portion 14 of the supporting body. The washers 31 and nuts 30^a are applied, the washers 31 manifestly acting to prevent lateral separation or vertical separation of the main support and clamping block device. The links 19 are then engaged upon the trunnions 18 and moved upwardly and toward each other and connected with the insulator string, not shown, by means of a conventional bolt which is likewise not illustrated as it forms no part of the present invention. The final step is to apply the cotter pins 23 which may not be vitally important but which are an additional safeguard to prevent the links from disengagement with the trunnions.

When the device is assembled in this manner it is apparent that the block device 16 will be spaced above the bottom of the depressed central portion of the stirrup-like main body and that the conductor will itself rest upon the curved seats 12. The block device 16 cannot move longitudinally with respect to the main body 10, is incapable of lateral displacement with respect thereto in a horizontal direction and has its vertical movability limited by the washers 31. Naturally under ordinary circumstances the weight of the cable is entirely adequate to hold it down in place but in case of some undulatory movement of the cable it is conceivable that the block device 16 might rise to the limited extent indicated which, however, would cause no harm. The point is that the block device 16, or clamping block whichever it may be called, fits loosely within the main body of the clamp so that the conductor will not be rigidly restrained in the clamp body but will lie loosely in it. As the clamping block 16 is relatively small and may possibly be formed of cast aluminum, it will be very light and will have but little effect on the conductor so that the latter may move quite freely with respect to the main body of the clamp. The point of advantage is that the clamping block is easily capable of being made accurately as far as its fit on the conductor is concerned so that a definite and precise holding power may be obtained. The holding power of course may be readily varied by varying the length of the clamping block, that is to say the effective length and not the actual length and this may readily be done by counterboring the ends so as to reduce the area in actual contact with the cable. Whether the ends be counterbored or not, it is preferable that they be somewhat flared or bell-mouthed for the protection of the conductor strands.

From the foregoing description and a study of the drawing it will be apparent that I have thus provided a very simply constructed and easily assembled and applied clamp which will be efficient in its holding action and which will entirely avoid mutilation of the conductor. It is thought that the construction, operation and advantages should be apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A suspension clamp comprising a main supporting body having means for mounting the same, and vertically movable means adapted to be tightly clamped upon a conductor and fitting loosely within said main supporting body, whereby the conductor will simply rest gravitationally upon the supporting body. 80
2. A suspension clamp comprising a main supporting body having means for mounting the same, and retaining means adapted to be tightly clamped upon a conductor and to fit loosely within said main supporting body, with the conductor resting upon the latter, said retaining means being restrained from all movement other than vertical with respect to said supporting body. 85
3. A suspension clamp for a conductor, comprising a main supporting body having means for mounting the same, and having spaced seats upon which the conductor may rest, and means rigidly clamped upon the conductor and fitting loosely within said main supporting body in spaced relation to the bottom thereof and operating to prevent longitudinal movement of the conductor with respect to the main supporting body while enabling the weight to be borne entirely by said seats. 90
4. A conductor suspension clamp comprising a main supporting body having conductor supporting seats at its opposite ends and having a socket between said seats, and means adapted to be rigidly clamped upon the conductor and fitting loosely within said socket. 95
5. A conductor suspension clamp comprising a main supporting body having a conductor receiving channel therein, said channel being formed to provide conductor seats at opposite sides of the transverse center, an enlarged socket in the body between said seats, and a block device adapted to be rigidly clamped upon the conductor and fitting within said socket. 100
6. A conductor suspension clamp comprising a main supporting body having means for pivotally supporting the same, said body having a conductor receiving channel and being centrally widened and deepened to provide a socket, seats at the opposite ends of the socket, and a separable block-like clamp engaged upon the conductor and fitting within said socket. 105
7. A conductor suspension clamp comprising a main supporting body having means for pivotally supporting the same, said body having a conductor receiving channel and being centrally widened and deepened to provide a socket, seats at the opposite ends of the socket, and a separable block-like clamp engaged upon the conductor and fitting within said socket in spaced relation to the bottom thereof. 110
8. A conductor suspension clamp comprising a main supporting body having means for pivotally supporting the same, said body having a central socket opening upwardly and provided in its bottom with openings, the body having channeled conductor engaging seats at the opposite ends of the socket, a sectional block-like member provided with bolts for clamping it upon the conduct- 115
- tor and fitting loosely within said socket with said bolts passing through said openings. 120
9. A conductor suspension clamp comprising a main supporting body, suspension means therefor, said body having channeled conductor receiving portions and provided centrally with a socket with spaced outwardly projecting sides, the body having conductor engaging seats adjacent the socket, and means secured upon the conductor and fitting loosely within the socket in spaced relation to the bottom thereof to enable the weight of the conductor to come upon said seats, said means comprising separable parts bolted together. 125
10. Means for supporting a conductor, comprising a member clamped rigidly thereon in surrounding relation thereto, and a supporting body equipped with suspension means and formed with seats adapted to engage against only the underside of the conductor, said body having a recess receiving said member for preventing longitudinal movement thereof with respect to the body. 130
11. Means for supporting a conductor, comprising a separable clamping member rigidly secured thereupon and a supporting body equipped with mounting means, said body having an open central portion receiving said clamping member and cooperating with the ends thereof to prevent relative longitudinal movement, said body being formed outwardly of the central open portion with seats engaging against the underside of the conductor. 135
12. Means for supporting a conductor, comprising a clamping member rigidly secured thereabout, and means located beyond the opposite ends of said clamping member and engaging against the underside of the conductor by gravity of the latter, said means cooperating with said clamping member for preventing longitudinal movement thereof and consequently the conductor with respect to said means, said clamping member being capable of vertical movement with respect to said means. 140
13. A conductor suspension means comprising a main supporting body provided with conductor supporting seats, and keeper means rigidly clamped upon the conductor and fitting within said body in unsecured relation thereto in spaced relation to the seats. 145
14. A conductor supporting means comprising a main supporting body having portions directly engageable beneath the conductor and gravitationally supporting the same, and means secured upon the conductor and received within the body in unsecured relation to the latter for restraining the conductor against longitudinal movement with respect to the body. 150
15. A suspension clamp comprising a supporting body equipped with suspension means and having stops at opposite sides of its transverse center, retaining means adapted to be secured upon a conductor and to fit within said body between said stops with the conductor engaged upon the body beyond the stops. 155

ROBERT L. McCOY. 140
